TOBACCO CURING SHED AND HEATING
PLANT THEREFOR

Herman W. Koester, Acme, N. C.

Application October 19, 1937, Serial No. 169,853

7 Claims. (Cl. 34—19)

This invention relates to a tobacco curing shed or barn and a heating plant therefor.

At the present time, the following method for the drying and curing of tobacco is commonly employed. The tobacco to be cured is first hung in sheds which are built for this purpose. The shed is heated by means of a furnace connected to a system of sheet iron flues near the bottom of the shed which act as radiators and thus supply heat to the tobacco for the purpose of drying and curing the same. Flues of the type described, frequently become red hot and tobacco leaves which may drop down on these hot pipes or flues from the sticks upon which they are hung, are apt to and often do cause the tobacco to burn and thus destroy the contents of the shed as well as the shed itself. Sheet metal flues of the type described are also objectionable in that they do not maintain an even temperature and they are apt to parch the leaves nearest to them, while at the same time the leaves which are more remote from the pipes are not cured on account of the lack of heat.

The present invention relates to a furnace and an associated heat radiating system formed from elongated brick and tile passageways which are located on the ground floor of a building suitable for the purpose intended. The furnace is adapted to burn either coal or wood. The shed is provided with a masonry or brick floor and the products of combustion are vented from the furnace by means of a chimney which is preferably provided with a damper for regulating the operation thereof.

It is the object of the present invention to provide a heating plant for a tobacco shed which is fire-proof, easy to operate and in the use of which an even temperature may be maintained in the shed for the purpose of producing a better grade of tobacco.

Another object of the invention relates to the provision of a heating plant for a tobacco drying shed which is economical in the use of fuel and which does not require constant attention in order to maintain an even heat in the shed.

A further object of the invention relates to the provision of a tobacco drying barn or shed in which the shed is provided with a suitable floor for preventing moisture from the ground from rising up through the tobacco and thus producing a spongy stem which makes a poor or unsalable grade of tobacco.

These and other objects of the invention will become more apparent and better understood after consideration has been given to the following detailed description of the invention taken

in connection with the drawings which show, merely by way of illustration, structure adapted for carrying out the objects of the invention.

In the drawings, Figure 1 is a front elevational view of a tobacco drying shed and a heating plant therefor illustrative of the invention; Figure 2 is a perspective view of one of the tiles which form the heat radiating elements of the heating system; Figure 3 is a plan view of the floor of the shed shown in Figure 1; and Figure 4 is an enlarged detail sectional view taken on line 4—4. Figure 3, of a flue or heat radiating passageway.

The tobacco drying shed or barn to which this invention relates and which is referred to generally by the numeral 1, forms an enclosing structure, the interior of which is provided with a plurality of tiers of tobacco supporting sticks or rafters 2. These sticks are preferably arranged parallel to each other in spaced relation and bunches of the tobacco to be cured are hung from the sticks in such manner so that the air in the shed may freely circulate about the tobacco. The shed is preferably provided with a brick or masonry floor 3 so as to prevent dampness in the ground from raising the humidity of the air inside the shed, as would occur if the ground were left uncovered as is now common practice.

The interior of the shed is heated by means of a furnace 4 of masonry construction which may be of fire brick or any other material of the type described which is suitable for this purpose. This furnace traverses the front wall of the shed and exteriorly of the shed it is provided with an opening 5 by means of which fuel may be supplied to the furnace. The furnace is adapted for the burning of coal or wood and the heated products of combustion are conveyed from the furnace to a passageway 6 extending rearwardly of the furnace to a point adjacent to the rear wall of the shed.

At the rear of the shed, the passageway 6 connects with two separate branches 7 and 8 contiguous to the rear wall of the shed and they in turn communicate with passageways 10 and 11 respectively, contiguous to the side walls of the shed. The last-named passageways extend toward the front wall of the shed near where they connect with upwardly inclining passageways 12 and 13 respectively. The passageways 12 and 13 connect with a single passageway 14 in communication with a chimney 15 carried by the furnace outside of the shed. The chimney may be pro-

vided with a damper (not shown) having an operating handle 16 outside the chimney.

The passageways 6 to 14 inclusive, as is best shown in Figure 4, are formed with brick side walls 17 and a tile top wall 18. The side walls may be formed from ordinary building brick and the top wall may be formed from ordinary three cell building tile, one of which is shown in Figure 2 of the drawings, the same being identified by the numeral 28. The building tile are laid cross-wise of the flue passageways so that their open ends are exposed to the air in the shed to permit the free circulation of air through the tile and thus provide for a relatively large area of heat radiating surfaces.

The tobacco shed heating system disclosed herein has certain important advantages over the more common type in which sheet iron flues are employed. The use of brick and tile prevents the heating surfaces from becoming excessively hot and good efficiency is achieved by increasing the area available for the radiation of the heat. The use of a floor covering as shown prevents the natural dampness in the ground from raising the humidity of the shed which is objectionable and harmful to the curing of the tobacco. Danger of fire is obviated because it is practically impossible to raise the temperature of the radiating surface to the point where it would ignite the tobacco.

The heat radiating flues have a relatively large thermal capacity and thus maintain a more even temperature in the shed even though the furnace is fired at relatively long intervals. The use of large radiation surfaces which are maintained at a relatively low temperature as in the case of the construction disclosed herein, provides for the even curing of all of the tobacco in the shed and there is no tendency to parch the leaves nearest the heat radiating flues, and not to cure the more remotely located tobacco, as is the case where such flues are formed from sheet metal and maintained at a relatively high temperature.

The foregoing description and the accompanying drawings to which it relates, describes what might be termed the preferred modes of practicing the invention. It is to be clearly understood, however, that the invention includes each and every novel feature or combination of novel features herein disclosed, subject only to the restrictions of the prior art, and that the invention may assume other forms and it is not to be limited to the particular and specific structure shown and described herein.

Having thus described my invention what I claim is:

1. In combination with a tobacco drying shed, a heating plant for the shed comprising, a combustion chamber, and an elongated passageway inside the shed in communication with said combustion chamber and a chimney in communication with the passageway for venting heated products of combustion from said chamber, said passageway being constructed in part at least of hollow tile with a portion at least of the walls thereof exposed to the heated products of combustion passing through said passageway and other walls arranged to constitute radiating surfaces of relatively large area, said tile being provided with open ends and placed so that the air in the shed may circulate therethrough and positioned so that any tobacco dropping upon the tile will land on the coolest portion of the tile.

2. In combination with a tobacco drying shed, a heating plant for the shed comprising, a com-

bustion chamber, and an elongated horizontally disposed passageway inside the shed in communication with said combustion chamber and a chimney in communication with the passageway for venting heated products of combustion from said chamber, said passageway being constructed in part at least of hollow tile open at its ends with a wall in contact with the heated products of combustion passing through said passageway and other walls arranged to constitute radiating surfaces of relatively large area, said tile each being formed with a plurality of open passageways and laid with its open ends exposed so that air in the shed may circulate through such passageways.

3. In combination with a tobacco drying shed, a heating plant for the shed comprising, a combustion chamber, and an elongated passageway inside the shed in communication with said combustion chamber and a chimney in communication with the passageway for venting heated products of combustion from said chamber, said passageway being of masonry construction with portions at least of the walls thereof of open channeled construction and constituting radiating surfaces of relatively large area for heating the air in the shed, the channeled portion of said walls having wall parts spaced outwardly from contiguous wall parts which are exposed to the products of combustion in the passageway.

4. In combination with a tobacco drying shed, a heating plant for the shed comprising, a combustion chamber, and an elongated passageway inside the shed in communication with said combustion chamber and a chimney in communication with the passageway for venting heated products of combustion from said chamber, said passageway being constructed of brick and building tile with one wall of the tile exposed to the heated products of combustion in the passageway and the open ends of the tile arranged to permit the passage of the air in the shed therethrough.

5. In combination with a tobacco drying shed, a heating plant for the shed comprising, a combustion chamber, and an elongated passageway inside the shed in communication with said combustion chamber and a chimney in communication with the passageway for venting heated products of combustion from said chamber, said passageway being constructed of brick with a top wall of building tile laid cross-wise with respect to the passageway with the open ends thereof exposed so as to permit the circulation of air through the channels of the tile.

6. In combination with a tobacco drying shed, a masonry floor for the shed, a furnace or firebox, a chimney, and heat radiating flues of masonry construction on the floor of the shed and in communication with the interior of said furnace and venting into said chimney, said flues being constructed in part at least from hollow building tile with the hollow interior of the tile open at its opposite ends to the atmosphere of the shed to permit the circulation of air therethrough.

7. In combination with a tobacco drying shed, a heating plant therefor comprising, a combustion chamber, a chimney, and a passageway inside the shed connecting said combustion chamber to said chimney and constituting a means for heating the interior of the shed, said passageway being constructed in part at least with a relatively thin wall section in contact at one side

with the heated products of combustion and exposed at its opposite side to the air in the shed and wall means located in closely spaced relation with respect to said thin wall section and thereby heated, said means constituting a relatively low temperature radiating surface and said thin wall section constituting a relatively high temperature radiating surface for transferring heat to

the interior of the shed by means of convection currents, said wall means being in a position to shield the tobacco in the shed from heat radiated directly by said thin wall section and also to guard the thin wall section against tobacco dropping thereon and thereby becoming ignited.

HERMAN W. KOESTER.
